PRODUCTION OF PLUTONIUM FLUORIDE FROM BISMUTH PHOSPHATE PRECIPITATE CONTAINING PLUTONIUM VALUES

Harrison S. Brown, Chicago, Ill., and Edward G. Bohlmann, Worthington, Ohio, assignors to the United States of America as represented by the United States Atomic Energy Commission

No Drawing. Filed Aug. 31, 1948, Ser. No. 47,142

1 Claim. (Cl. 23—14.5)

This invention is concerned with an improved method of separating plutonium from contaminating elements normally associated with plutonium in neutron-irradiated uranium.

The word "plutonium," as hereinafter used in the specification and claims refers to the element of atomic number 94 and to the compounds thereof, unless the context indicates clearly that plutonium is referred to in its metallic state.

Natural uranium is composed of three isotopes; namely U^{234} , U^{235} , and U^{238} , the latter being in excess of 99% of the whole. When U^{238} is subjected to the action of slow or thermal neutrons, a fourth isotope, U^{239} , is produced having a half-life of twenty-three minutes and undergoing beta decay to Np^{239} , which in turn decays with a half-life of two and three-tenths days to yield plutonium. In addition to the formation of 94^{239} , there are simultaneously produced other elements of lower atomic weight known as fission fragments. These fission fragments are composed of elements having atomic numbers from about 32 to 64. The elements of this group, as originally produced, are considerably overmassed and undercharged and hence are highly unstable. By emission of beta particles accompanied by gamma radiation, these elements transform themselves into isotopes of these various elements having longer half-lives. The resulting materials are commonly known as fission products.

Various radioactive fission products have half-lives ranging from a fraction of a second to thousands of years. Those having very short half-lives may be substantially eliminated by aging the material for a reasonable period before handling. Those with very long half-lives do not have sufficiently intense radiation to endanger personnel protected by moderate shielding. On the other hand, the fission products having half-lives ranging from a few days to a few years have dangerously intense radiations which cannot be eliminated by aging for practical storage periods. These products are chiefly radioactive isotopes of Sr, Y, Zr, Nb, Te, I, Cs, Ba, La, Ce, and Pr.

It may be readily seen that plutonium, as produced by the process generally set forth above, is contaminated with considerable quantities of uranium and fission products. In fact, the plutonium constitutes only a very minor portion of the irradiated mass, i.e., less than 1% thereof. In view of such a low concentration of plutonium in the irradiated metal and the highly radioactive character of the fission products present, it becomes apparent that the procedure employed to recover

2

that element must be highly efficient in order to be at all practicable.

There have been devised a number of procedures for the removal and concentration of plutonium from extremely dilute solutions thereof. In general, such methods involve the formation in said dilute solutions of various insoluble compounds capable of carrying plutonium in one of its valence states. The carrier precipitate and plutonium thus obtained are then dissolved 10 and the plutonium converted to another valence state, in which state it is soluble in the presence of said carrier. The carrier is then re-precipitated from the new solution, thus removing the fission products present in this solution, but leaving the soluble plutonium in solution. Thereafter, the plutonium may be separated from the solution directly as a plutonium compound or the plutonium may be converted to the valence state in which it is insoluble with the aforementioned carrier and may be removed from the solution with that carrier. 15 This carrier precipitate may again be dissolved and the plutonium purified further, if considered necessary or desirable, by repeating the above cycle. A carrier precipitate which carries plutonium is usually referred to as a "product" precipitate, while a carrier precipitate which removes elements other than plutonium, leaving the plutonium in the solution is usually referred to as a "by-product" precipitate.

The precipitation method of separation is usually divided into four steps. The steps are: Extraction, in 20 which the plutonium is separated from the uranium and most of the fission products; decontamination, in which the plutonium is separated from the remaining fission products; concentration, in which the ratio of carrier precipitate or containing solution to plutonium is greatly 25 reduced; and isolation, in which the final plutonium compound is precipitated directly from solution.

One of the most important plutonium precipitation processes is the bismuth phosphate process. In this process the neutron-irradiated uranium mass, after suitable aging, is dissolved in nitric acid to form a uranyl nitrate hexahydrate solution. A bismuth phosphate precipitate is then formed in and separated from this solution, carrying with it plutonium in a valence state less than 5 and fission products which are phosphate-insoluble, particularly zirconium and niobium. This precipitate is then redissolved in nitric acid, the plutonium converted to the hexavalent state, and a by-product bismuth phosphate precipitate carrier formed in, and separated from, this solution, carrying with it the phosphate-insoluble fission products. The plutonium contained in the supernatant solution is then reduced to the tetravalent state and carried from the solution with a bismuth phosphate carrier precipitate. This precipitate is then dissolved in nitric acid, the plutonium oxidized to the hexavalent state, and a bismuth phosphate by-product carrier precipitate separated from the solution. Following this, the plutonium is reduced to the tetravalent state and separated from the solution with a lanthanum fluoride carrier. This carrier of lanthanum fluoride is metathesized with an alkali metal carbonate or hydroxide, the resulting mixed lanthanum and plutonium hydroxides dissolved, and the plutonium precipitated directly from the solution without a carrier.

While this type of plutonium separation process is high-

ly efficient in the separation of plutonium from contaminants normally associated with plutonium in neutron-irradiated uranium, particularly the radioactive fission products, there are certain disadvantages and inconveniences in the use of this process. The procedure is obviously cumbersome and time-consuming, since it requires a number of precipitation steps in order to obtain the plutonium in a pure state. It requires a vast amount of reagents and the process leaves a large quantity of radioactive and waste by-products, which are difficult to dispose of safely. It will be readily apparent that any process for separating plutonium from contaminants with a lesser number of steps than the precipitation process would have great utility.

It is an object of this invention to provide a convenient and efficient method of recovering plutonium from impurities associated therewith in a neutron-irradiated uranium mass.

It is a further object of our invention to provide a method that will effectively separate plutonium from fission products and other impurities normally associated therewith, in a small number of operations.

Additional objects of our invention will be apparent as the present description proceeds.

Broadly, this invention comprises the hydrofluorination and fluorination at elevated temperatures of a bismuth phosphate mass containing plutonium and phosphate-insoluble fission products, whereby fission products, which form relatively volatile fluorides, are volatilized away from the bismuth-phosphate, plutonium-containing mass. The carrier mass is then treated with anhydrous fluorine at elevated temperatures, whereby the plutonium is oxidized and volatilized as its higher fluorides and thus separated from the less volatile constituents of the mass.

In accordance with the preferred embodiment of our invention, neutron-irradiated uranium is aged for from sixty to ninety days, thereby substantially converting the neptunium present to plutonium and permitting the most active fission products to decay to more stable isotopes. The uranium mass is then dissolved in a suitable acid, for example, nitric acid. The uranium is normally present in such solution as the uranyl ion and the plutonium as the tetravalent ion. However, to insure that the plutonium is present in a valence state less than +5, the solution may be treated with a reducing agent, such as formic acid or sodium nitrite in the presence of sulfuric acid, whereby the dissolved plutonium is converted substantially completely to the tetravalent state. A bismuth phosphate precipitate is then formed in the uranyl nitrate hexahydrate solution and separated therefrom. This bismuth phosphate precipitate carries with it the plutonium present and the fission products which are phosphate-insoluble. The uranyl ion and a substantial portion of the fission products are phosphate-soluble and so remain in the solution after the separation. Since the uranium is greater than 99% of the total mass, this results in a great reduction in the amount of foreign products which contaminate the plutonium. The fission activity is also reduced by this step by about 87%. The 13% of fission product activity carried with the bismuth phosphate is attributed largely to zirconium and niobium isotopes. The bismuth phosphate plutonium carrier precipitate thus obtained is dried and thereafter placed in a suitable fluorination reactor.

The dried precipitate is then subjected at elevated temperatures, for example at a range of 500-600° C., to the action of hydrogen fluoride, preferably in the anhydrous state, whereupon the niobium present is converted to the volatile niobium fluoride and readily separated from the remainder of the solid mass. Any traces of other fission products, the fluorides of which have high volatility, may also be separated at this point. These may include As, Se, Br, Sb, Te, and I. The radioactive inert gases, Kr and Xe, will also be completely removed by this step. Plutonium present in the mass will be substantially con-

verted to the tetravalent plutonium fluoride, which however is not volatile below 600° C. The mass is then treated with fluorine at temperatures of about 290° C. or above and preferably between about 400-500° C., whereupon the lower plutonium fluoride is converted to the higher volatile fluoride (probably the penta- or hexa-fluoride), volatilized and thus effectively separated from the less volatile impurities in the mass, particularly radioactive zirconium the plutonium fluoride is condensed at below 290° C. The bismuth fluoride residue is distilled off at about the same temperature as the plutonium fluoride and so other procedures must be used in separating the plutonium and bismuth fluorides obtained by this process. The hydrogen fluoride and fluorine used in this process should be free from oxygen and water vapor in order to avoid the complications caused by oxyfluoride formation.

Our invention may be further illustrated by the following specific example.

Example

To 25 ml. of a nitric acid solution of neutron-irradiated uranium, which has previously been treated with sodium nitrite in the presence of H_2SO_4 to insure that the plutonium present is in an oxidation state of less than +5, is added 1 g. of bismuth nitrate and the solution made 0.7 M in H_3PO_4 . The resulting mixture is agitated for 10 minutes at 75° C. and bismuth phosphate plutonium carrier precipitate thus formed is separated from the solution by centrifugation. The solid residue thus obtained which contains approximately 5.0 mg. of plutonium together with fission products is next placed in a drying oven at a temperature of about 100° C. and allowed to remain until substantially anhydrous. Thereafter the dry bismuth phosphate plutonium carrier precipitate is placed in a nickel tube fluorination reactor of conventional design and anhydrous hydrogen fluoride is introduced at a rate of approximately 0.5 liter per hour for a period of two hours at 500° C. Under these conditions the plutonium present is converted to plutonium tetrafluoride which, however, is not volatile below 600° C. and thus remains with the mass. Niobium and other volatile impurities, however, are volatilized by this step. Anhydrous fluorine is next introduced at a rate of about 0.3 liter per hour at a temperature of 525° C. under which conditions the plutonium tetrafluoride is transformed to a volatile fluoride and is collected in a suitable receiving vessel at a temperature below 275° C. The bismuth fluoride formed by this fluorination step accompanies the plutonium and is collected with it. The remaining fission products which have fluorides less volatile than the higher plutonium fluorides, are left as a residue in the reaction chamber. The plutonium recovered in this manner represents approximately 95% of that originally present in the uranyl nitrate hexahydrate solution.

It will be apparent to those skilled in the art that the method of recovering plutonium, as generally set forth above, provides a simple and practical procedure for the separation of plutonium from radioactive fission products. It will also be noted that the radioactive fission products are recovered in a concentrated and easily handled form.

While this invention has been illustrated by certain applications, it is not desired to be specifically limited thereto, since it is manifest to those skilled in the art to which the present invention is directed, that it is susceptible to numerous alterations and modifications without departing from the scope thereof. While it is illustrated as a step in a continuous process for the separation of plutonium from neutron-irradiated uranium, the process may also be suitably used for the separation of plutonium from any contaminant which forms a fluoride having a boiling point different than that of a higher fluoride of plutonium.

What is claimed is:

A process of producing a mixture of bismuth and plu-

tonium fluorides free from fission products from a bismuth phosphate carrier precipitate containing plutonium values in a valence state of less than +5 and fission product values, comprising drying said precipitate; subjecting said precipitate to the action of hydrogen fluoride at a temperature of between 500 and 600° C. whereby the plutonium is converted to plutonium tetrafluoride and the fission products to the fluorides some of which volatilize away from a residue containing said bismuth phosphate, plutonium tetrafluoride and nonvolatile fission product fluorides; contacting the residue with anhydrous fluorine at a temperature of between 400 and 500° C.

whereby a volatile plutonium fluoride and a volatile bismuth fluoride form and distill off leaving the substantially nonvolatile fission product fluorides; and condensing said mixture of plutonium fluoride and bismuth fluoride by cooling to below 290° C.
